F. G. Fischer, atty.

UNITED STATES PATENT OFFICE

2,561,099

INSULATION CUTTER

John F. Costelow, Kansas City, Mo.

Application January 15, 1947, Serial No. 722,121

6 Claims. (Cl. 30—91)

1

My invention relates to devices for cutting insulating sheaths or coverings of cables longitudinally at their ends, so that access may be had to the enclosed conductors, for the purpose of connecting the ends thereof to various electrical instruments or for splicing them to the ends of other conductors.

My device is capable of cutting sheaths of different thicknesses and diameters made from various kinds of material, such, for example, as fabrics, lead, or rubber.

The present invention is an improvement on the insulation cutter disclosed by my copending application, Serial No. 624,820, filed October 26, 1945, now Patent No. 2,452,734, issued November 2, 1948. Objects of the instant invention are to improve and reduce the number of parts entering into the construction of the device by combining the frame and handle thereof in a single streamlined casting and dispensing with a number of other parts, to enclose most of the working parts in the frame of the device where they will be protected from damage due to the rough usage to which tools of this character are subjected, to provide a blade with a dull end that can be forced into a sheath to the enclosed individual conductors without cutting the respective insulation coverings of the latter, means for adjusting the blade to accommodate cables of different diameters, and to provide a seat which can be adjusted to support cables of various sizes, one at a time, while being acted upon by the blade.

Other objects will hereinafter appear and in order that the invention may be fully understood, reference will now be had to the accompanying drawing, in which:

Fig. 1 is a side elevation of the device, with part of a cable located therein and partly slit near one end by the blade.

Fig. 2 is a broken top plan view of the device.

Fig. 3 is a broken longitudinal section on line 3—3 of Fig. 2, with the addition of part of a cable.

Fig. 4 is a cross section on line 4—4 of Fig. 2, with the addition of a cable in cross section.

Fig. 5 is a detail perspective view of the blade and a holder therefor.

Fig. 6 is a fragmentary longitudinal section of the frame of the device.

Fig. 7 is a detail perspective view of an adjustable U-member provided with a seat for supporting, one at a time, cables of different diameters.

In order to avoid confusion in the following description and claims as to the position and direction of movement of parts, it will be assumed

2

that the device is disposed in a horizontal position as disclosed by Fig. 1.

In carrying out the invention I provide a frame 2 with an integral handle 4, having a longitudinal groove 6, registering at its forward end with a bore 8, extending longitudinally through the lower portion of the frame 2 and which cooperates with the groove 6 in guiding and supporting an insulated cable such, for example, as the cable A, covered by an insulating sheath B enclosing a plurality of wire conductors C, with individual coverings of insulation D. The sides of the frame 2 and the handle 4 are preferably flush with each other and the front and rear edges of the frame taper upwardly as disclosed by Fig. 1, to give the device a streamline appearance. The frame 2 includes a pair of spaced side walls 10 united by the lower portion of the frame and provided at their outer sides with vertical grooves 12 which extend downward from the upper margins of the side walls 10 to opposite sides of a recess 14 formed in the lower portion of the frame and communicating with the bore 8.

A U-member 16 has spaced upright arms 18 mounted for vertical adjustment in the grooves 12. The arms 18 are provided at their upper side portions with vertical slots 20, through which set screws 22 extend and are threaded in the side walls 10 of the frame 2. The set screws 22 have heads 23 adapted, when adjusted inwardly, to clamp the outer surface of the arms 18 and thus firmly hold the U-member 16 at any point of its vertical adjustment. Preferably the slots 20 have open upper ends as shown, to permit removal of the U-member 16 if desired, without necessitating removal of the set screws 22 from the side walls 10. The U-member 16 is provided at its lower inner portion with a V-seat 24 for supporting cables of different diameters, one at a time. The V-seat 24 is adapted to prevent each cable placed therefrom from shifting laterally while a blade 26 is being forced down to penetrate the upper thickness of the sheath.

The blade 26 is secured to a blade holder 30 by suitable means such, for instance, as screws 32. The blade 26 has two cutting or sharp edges 33, tapering downward to a dull or blunt end 38 so that when the blade is pushed downward through the upper thickness of the insulation B, both of the sharp edges 33 will actually cut the insulation while the blunt end 38 pushes the inner conductors C downward and away from the cutting edges 33. The blunt end 38 also performs the foregoing operation during slitting of the insulation longitudinally, thereby avoiding the

necessity of using the fingers of the worker to pull the sides of the slit portion apart to observe the condition of the insulation on the conductors C. Thus danger of cutting the finger on the sharp edges 33 is avoided and the time and labor heretofore required in frequent inspections of the conductors C during slitting of the outer insulation B is saved. A slot 34 extending through the upper wall 36 of the bore 8 permits the blade 26 to enter said bore and act on the insulation B of the cable.

The blade 26 is actuated by a hand lever 40 extending forwardly between the spaced walls 10 and mounted at its forward end upon a pivot 42 extending transversely through axially aligned holes in the walls 10. The hand lever 40 is provided at its forward portion with a loop 44, Fig. 2, to receive the lower part of the blade holder 30 which is connected by a pivot 46 to opposite sides of the loop 44, Fig. 4. The blade holder 30 operates between the spaced walls 10 and is provided at its upper portion with shoulders 48, projecting in opposite directions over the loop 44 and slidably mounted in a pair of opposed vertical grooves 50 in confronting sides of the walls 10. In order that cables of different diameters may be acted upon, the U-member 16 is adjusted downward to lower the seat 24 and the hand lever 40 is adjusted upward to lift the blade holder 30 and the blade 26, to accommodate a large cable. For smaller cables the adjustments are reversed. Means for obtaining micrometer adjustment of the blade 26, comprise a threaded member 52 projecting upwardly from the blade holder 30 and provided with a rotatable member 54 bearing on top of the side walls 10 of the frame 2 and adapted when rotated in one direction to force the threaded member 52 and blade holder 30 downward, or lift them when the rotatable member 54 is turned in a reverse direction. A coiled spring 56, surrounding the threaded member 52 and interposed between the blade holder 30 and rotatable member 54, exerts sufficient pressure on the latter to prevent accidental rotation thereof. A scale 58 on one side of the frame 2 and an index 60 on the adjacent arm 18 are provided to assist the operator in locating the lower end 38 of the blade 26 with respect to the cable resting upon the underlying seat 24, so that downward movement of the blade may be checked on penetration of the upper thickness of the sheath.

In practice, a cable such as A, may be inserted in the bore 8, through either end of the latter. Assuming that the cable is inserted through the left end of the bore, it is pushed inward past the seat 24 and the blade 26 a distance equal to the length of the slot which it is desired to cut in the sheath B. The hand lever 40 is then pushed downward to force the dull terminal 38 of the blade 26 through the upper thickness of the sheath B and against one of the upper conductors C or between two upper conductors. Downward movement of the lever 40 is then checked by the rotatable member 54 contacting the top of the frame 2. The handle 4 is then firmly grasped with one hand and the cable A is grasped with the other hand and pulled from the left end of the bore 8, thereby completing the slit D, partly completed as shown by Fig. 3.

From the foregoing description taken in connection with the accompanying drawing, it will be understood that one improvement of the present invention resides in combining the frame 2 and the handle 4 in one streamlined member with aligned groove 6 and bore 8, instead of two mem-

bers which are separately produced and assembled for use. The adjustable U-member 16 with seat 24 also constitutes other improvements as they may be adjusted vertically relative to the upper wall 36 of the bore 8, to accommodate cables of different diameters and thus dispense with the use of tubular inserts of various diameters. Other improvements reside in the blade holder 30 and double cutting edged blade 26 with the dull terminal 38, to avoid cutting the insulation on the inner conductors C. A further improvement resides in the loop 44 of the lever 40 and pivotally connecting the blade holder 48 thereto, thus dispensing with link connections and forked ends of the former located on the outside of the frame where they were liable to damage.

While I have illustrated and described a preferred form of my device, I reserve all rights to such changes and modifications thereof as properly fall within the scope of the invention as claimed.

Having thus described my invention, what I claim and desire to secure by Letters Patent, is:

1. An insulation cutter comprising a frame 25 with a bore extending longitudinally therethrough, a blade adjustably mounted in the frame, a blade holder adjustably mounted in the frame and to which the blade is secured, a lever extending into an opening in the frame and provided with a loop through which the blade holder extends, and independent means 30 pivotally connecting the lever to the frame and the blade holder whereby the latter and the blade may be adjusted relative to an insulated cable inserted in the bore.

2. An insulation cutter comprising a frame 40 with a bore extending longitudinally therethrough, a blade adjustably mounted in the frame, a blade holder adjustably mounted in the frame and to which the blade is secured, a lever extending into an opening in the frame and provided with a loop through which the blade holder extends, independent means pivotally connecting the lever to the frame and the blade holder whereby the latter and the blade may be quickly adjusted relative to the bore, and means 45 associated with the frame and the blade holder for micrometrically adjusting the blade holder and the blade relative to the passageway.

3. An insulation cutter comprising a frame including two spaced side walls and a longitudinal bore, a blade in the frame, a blade holder carrying the blade and slidably mounted in confronting grooves in the side walls, a hand lever extending between the spaced walls of the frame, a transverse member secured in the spaced walls and upon which the hand lever is operably mounted, a loop on the hand lever through which the blade holder freely extends, and pivotal means connecting the blade holder to the loop for movement of the blade holder and the blade relative to the frame and to an insulated cable inserted in the bore and adapted to be grasped and withdrawn from the bore and thereby slit the insulation.

4. An insulation cutter comprising a frame including two spaced side walls and a longitudinal bore, a blade in the frame, a blade holder carrying the blade and slidably mounted in confronting grooves in the side walls, a hand lever extending between the spaced walls of the frame, a transverse member secured in the spaced walls and upon which the hand lever is operably mounted, pivotal means connecting the blade holder 70 to the hand lever whereby rapid adjustment of

the blade holder and the blade relative to the bore may be had, and micrometer adjusting means whereby fine adjustment of the blade holder and the blade relative to the bore may be had, said micrometer adjusting means comprising a member threaded into the blade holder, a rotatable member mounted upon said threaded member and bearing upon the spaced walls, and an expansible spring encircling the threaded member and interposed between the blade holder and said rotatable member.

5. In an insulation cutter comprising a frame having two spaced side walls united by a bottom portion of the frame, said bottom portion having a bore extending longitudinally therethrough and a recess communicating with the bore, a U-member having a pair of spaced arms vertically slidable on the spaced side walls of the frame and its lower portion movably arranged in the recess, adjustable means for securing the U-
20 member to the frame at any point of its vertical movement, a blade in the frame adapted to project through a slot in the lower portion of the frame and which communicates with the bore at a point above the bottom of the U-member, and means in the frame for adjusting the blade vertically relative to an insulated cable inserted in the bore and resting upon the bottom of the U-member, said cable being adapted to be grasped and withdrawn from the bore, thereby slitting the insulation on the cable.

6. In an insulation cutter comprising a frame having two spaced side walls united by a bottom portion of the frame, said side walls having
